HAIR WAVING DEVICE

Laura M. Chandonnet, Haverhill, Mass.

Application August 6, 1938, Serial No. 223,417

15 Claims. (Cl. 132—31)

This invention relates to a device to form waves or curls in hair.

One object of my invention is to provide a device that will form waves of the so-called permanent type in the hair of a person, whether it is long or short, with more security and comfort to the person whose hair is being waved. Another object is to provide such a device that will start the wave closer to the part in the hair than could safely be done heretofore, and will make the waves more pronounced, and will make the operator a more complete master of the shape, length and degree of pronouncement of the waves. Another object is to make my device light in weight and of such construction that it is simple and economical, and quicker in operation than devices now used, and composed of parts or sections that can readily be assembled and disassembled, and are adaptable for use one or more sections at a time. This latter feature is particularly desirable where the hair is short, or a wave is desired in new hair close to the scalp only which has grown since a wave was previously made in the hair, for one section only will best do this.

The foregoing and other objects which will appear as the nature of the invention is better understood, may be accomplished by a construction, combination and arrangement of parts such as is disclosed by the drawings and specifications. The nature of the invention is such as to render it susceptible to various changes and modifications, and, therefore, I am not to be limited to said disclosures; but am entitled to all such changes therefrom as fall within the scope of my claims.

In the drawings:

Figure 1 is a perspective view of the foremost section constituting my hair waving plate. Figure 2 is a similar view of an intermediate section thereof, and Figure 3 is a similar view of a rear member for said plate.

Figure 4 is a perspective view of a retainer member for said sections. Figure 5 is a perspective view of my device in use, showing one retainer member only partly broken away.

Figure 6 is a sectional view taken on the line 6—6 of Figure 5, and showing my device with the retainer member for the intermediate section and the clamping member for the rear section in position for use.

Figure 7 is a perspective view of a modified form of retainer member equipped with electrical heating units.

As illustrated, there is a hair waving plate P

consisting of one or more sections depending upon the length of the hair to be waved. The foremost hair curling section 12 consists of a bottom 14 and two upstanding sides 15 extending therefrom and spaced apart. Teeth or pin members 16 extend upwardly from said sides a short distance such as $\frac{1}{16}$ ", there being a plurality of said teeth 16 in each side 15, spaced apart and preferably extending the full length of said sides. At the two ends of said waving plate P slots or 10 slideways 17 are formed by bending over a portion of the material forming the bottom 14 of said plate P so that it extends below said bottom and is spaced therefrom. Ears 18 extend outwardly at both ends to make connection with a 15 protector member commonly used in waving hair.

The next or intermediate hair curling section 20 has a bottom 21, one upstanding side 22 having teeth 23 similar to and corresponding with teeth 16. At the front part of said section 20 a 20 slide or connecting tongue 24 extends outwardly and is adapted to enter said slideways 17 in the foremost section whereby said two sections 12 and 20 are joined together. This intermediate section 20 likewise has slideways 25 similar to 25 the said slideways 17 which also serve as stops when they abut slideways 17 at the point where said slide member 24 has fully entered said slideway 17. As many of these intermediate sections 20 may be used as are necessary to wave the hair 29 H, depending largely on the length of the hair.

When the hair is short, said foremost section 12 alone is used and constitutes the hair waving plate P. Likewise when a customer has had a permanent wave and later on desires only the 25 newly grown hair to be waved said section 12 is the only section the operator needs to use.

A rear member 30 is provided which has a bottom 31 and a slide or connecting member 32 similar to member 24 which is adapted to enter 40 said slideways 25 to thereby connect with said intermediate section 20, thereby completing said hair waving plate P. At the two ends of said end member 30 are upstanding bracket members 33 in which slots 34 are formed, which are 45 adapted to receive and support an end curler rod or clip 37 commonly used in hair waving at the ends of the hair. In said rear member 30 recessed members 38 may be formed to receive a removable holder 39 used for convenience in 50 handling my device and for placing it on the head of the customer.

For each said section 12 and 20 there is a companion hair retaining presser or holder member P having a clamp to hold it in position which 55

consists of two jaws 41 that are controlled by handles 42, which have overlapping ears 43 at each end through which a rod 45 passes around which is a coiled spring 46, held under such tension with relation to said jaws 41 that they are normally held closed. Extending from one said jaw 41 is a retainer plate 47 which is adapted to fit over the bottom of said sections between said upstanding sides to thereby keep the hair H in place. Said plates 47 preferably have spring fasteners 49 at each end fastened as at 50 thereto which hold said retainer plates 47 in close companionship with said waving plate sections, although separate clamps could be used. Between said retainer plates 47 and the bottoms of said waving plate sections the usual exothermic or chemical heat generating pads may, of course, be used, and the retainer member P may be equipped with electrical resistance units 60 as shown in Figure 7 of the drawings. To permit the escape of steam, perforations 53 are formed in the jaws 41 of said clamp P. There is a clamping member C for said rear members 30 having two jaws 41, two handles 42, ears 43, rod 45 and spring 46 similar to those for said presser P. Extending from one said jaw 41 of clamp C is a crescent-shaped hood 54 which receives and fits over said end curler rod 37.

The parts for my device may be made of any suitable material, preferably of some light, pliable metal such as aluminum.

What I claim is:

1. A hair waving device comprising in combination a hair waving plate having upstanding sides spaced apart having teeth projecting upwardly, a bottom between said sides, and a companion retainer member having a plate adapted to fit between said sides and over said bottom having clamping means adapted to clamp on one of said sides and hold said retainer plate in position between said sides.

2. A hair waving device comprising in combination a hair waving plate having upstanding sides spaced apart having teeth projecting upwardly, a bottom between said sides, and a companion retainer member having a plate adapted to fit between said sides and over said bottom having two clamping jaws adapted to clamp on one of said sides and hold said retainer plate member in position between said sides, and means tending to normally hold said jaws in close relationship.

3. A hair waving device comprising in combination a hair waving plate having upstanding sides spaced apart having teeth projecting upwardly, a bottom between said sides, and a companion retainer member having two jaws and a plate extending from one said jaw adapted to fit between said sides and over said bottom having clamping means adapted to clamp on one of said sides and hold said plate in position between said sides, and means tending to normally hold said jaws in close relationship.

4. A hair waving device comprising in combination a hair waving plate having upstanding sides spaced apart having teeth projecting upwardly, a bottom between said sides, and a companion retainer member having a plate adapted to fit between said sides and over said bottom having clamping means adapted to clamp on one of said sides and hold said plate in position between said sides, and movable clamping means carried by said plate adapted to clamp it to said hair waving plate.

5. A hair waving device comprising a hair wav-

ing plate having a bottom and a plurality of upstanding members spaced apart adapted to retain portions of hair in a predetermined position, and a companion retainer member having a plate adapted to fit between said upstanding members and over said bottom having clamping means adapted to clamp on one of said upstanding members and hold said plate in association with said hair waving plate. 5

6. A hair waving device comprising in combination a hair waving plate embodying a plurality of sections, said sections having means whereby they can be moved into and out of association with each other, said hair waving plate when said sections are in association with each other having a plurality of upstanding sides spaced apart having teeth projecting upwardly, and a bottom between said sides, and companion retainer members for said sections adapted to fit between said sides and over said bottom, and means to hold said retainer members to said sections. 10

7. A hair waving device comprising in combination a hair waving plate embodying a plurality of sections, said sections having means whereby they can be moved into and out of association with each other, said hair waving plate when said sections are in association with each other having a plurality of upstanding sides spaced apart having teeth projecting upwardly, and a bottom between said sides, and companion retainer members for said sections adapted to fit between said sides and over said bottom, having clamping means adapted to clamp on said sides and hold said retainer members to said hair wav- 25

ing plate. 30

8. A hair waving device comprising in combination a hair waving plate embodying a plurality of sections, said sections having slideways and slides adapted to enter said slideways whereby they can be moved into and out of association with each other, said hair waving plate when said sections are in association with each other having a plurality of upstanding sides spaced apart having teeth projecting upwardly, and a bottom between said sides, and companion retainer members for said section adapted to fit between said sides and over said bottom, having means to hold said retainer members to said sections. 40

9. A hair waving plate for a hair waving device embodying a foremost section having two upstanding sides spaced apart having teeth projecting upwardly, a bottom between said sides, and a slideway formed in said section, an intermediate section having an upstanding side having teeth projecting upwardly, a bottom, a slide member extending outwardly from said bottom and spaced from the latter mentioned side and adapted to enter said foremost section slideway, and a slideway formed in said intermediate section, and a rear member having a slide member adapted to enter said intermediate section slideway. 50

10. A hair waving plate for a hair waving device embodying a foremost section having two upstanding sides spaced apart having teeth projecting upwardly, a bottom between said sides, and a slideway formed in said section below said bottom, an intermediate section having an upstanding side having teeth projecting upwardly, a bottom, a slide member extending outwardly from said bottom and spaced from the latter mentioned side and adapted to enter said foremost section slideway, and a slideway formed in said intermediate section below the bottom there- 60

- of and a rear member having a bottom and a slide member extending outwardly from said bottom and adapted to enter said intermediate section slideway.
5. 11. A hair waving plate for a hair waving device embodying a foremost section having two upstanding sides spaced apart having teeth projecting upwardly, a bottom between said sides, and a slideway formed in said section, an intermediate section having an upstanding side having teeth projecting upwardly, a bottom, and a slide member extending outwardly from said bottom and spaced from the latter-mentioned side and adapted to enter said foremost section slide- 5
- 10 way.
12. A hair waving plate for a hair waving device embodying a foremost section having two upstanding sides spaced apart having teeth projecting upwardly, a bottom between said sides, and a slideway formed in said section, an intermediate section having an upstanding side having teeth projecting upwardly, a bottom, and a slide member extending outwardly from said bottom and spaced from the latter-mentioned side and adapted to enter said foremost section slide- 10
- 15 way, said slideway being a continuation of the material forming said bottoms bent downwardly and under and spaced from said bottoms. 15
13. A hair waving device comprising in combination a hair waving plate and retainer means adapted to hold hair in position on said plate, said hair waving plate embodying a foremost section having two upstanding sides spaced apart having teeth projecting upwardly, a bottom between said sides, and a slideway formed in said section, an intermediate section having an upstanding side spaced from said two sides when said intermediate section is in association with said foremost section and having teeth projecting upwardly, a bottom, a slide member extending outwardly from said bottom and adapted to enter said foremost section slideway, and a slideway formed in said intermediate section, and a rear member having a bottom and a slide member extending outwardly from said bottom and adapted to enter said intermediate section slideway, a retainer member embodying a plate for said foremost section and a retainer member embodying a plate for said intermediate section, said plates being adapted to fit over a said bottom and between said sides of said section, said retainer members having clamping means adapted to clamp on said sides to hold said plates in position between said sides. 20
14. A hair waving device comprising in combination a hair waving plate and retainer means adapted to hold hair in position on said plate, said hair waving plate embodying a foremost section having two upstanding sides spaced apart having teeth projecting upwardly, a bottom between said sides, and a slideway formed in said section, an intermediate section having an upstanding side spaced from said two sides when said intermediate section is in association with said foremost section and having teeth projecting upwardly, a bottom, a slide member extending outwardly from said bottom and adapted to enter said foremost section slideway, and a slideway formed in said intermediate section, and a rear member having a bottom and a slide member extending outwardly from said bottom and adapted to enter said intermediate section slideway, a retainer member for said foremost section and a retainer member for said intermediate section, each said retainer member having a plate adapted to fit over a said bottom and between said sides of said sections and clamping means adapted to clamp on one of said sides and hold said plates in position between said sides, and a clamp member having clamping means adapted to clamp on a said side of a said intermediate section and having a hood at the outer extremity thereof extending over said rear member bottom and adapted to receive said end curling rod. 25
